Primary Examiner—M. N. Pandozzi*Attorney, Agent, or Firm*—Townsend and Townsend and Crew LLP[57]*CLAIM

The ornamental design for a buffet plate and beverage holder, as shown and described.

DESCRIPTION

FIG. 1 is a top perspective view of a buffet plate and beverage holder showing my new design;

FIG. 2 is a top plan view thereof;

FIG. 3 is a front elevational view thereof;

FIG. 4 is a right side elevational view, the left side elevational view being a mirror image;

FIG. 5 is a rear elevational view thereof; and,

FIG. 6 is a bottom plan view thereof.

The broken line showing of a cup in FIGS. 1, 3, 4 and 5 is for illustrative purposes only and forms no part of the claimed design.

1 Claim, 2 Drawing Sheets*FIG. 1.FIG. 2.FIG. 3.*FIG. 4.

FIG. 5.

FIG. 6.
